LAWRENCE S. WILBUR, OF EVANSTON, ILLINOIS, ASSIGNOR TO NATIONAL RAIL JOINT CORPORATION, OF CHICAGO, ILLINOIS, A CORPORATION OF ILLINOIS

MOBILE REFORMING PLANT

Application filed October 7, 1929. Serial No. 397,879.

This invention relates generally to the reforming or reclaiming of worn-out railway service parts as, for example, rail splice bars.

In track maintenance in railroad systems, particularly where the traffic is heavy, the worn-out rail splice bars must be frequently replaced in order to prevent loose, bumpy and noisy joints. The procedure is usually to remove the worn plates and substitute new ones, the worn plates being collected and piled along the right of way. If the plates are not too much worn, they can readily be restored to usefulness by being reformed in a hydraulic or hydro-pneumatic press. However, such reforming machinery is not always close by and if the worn bars must be shipped a considerable distance for reforming treatment and then returned, a point is reached where it would be cheaper to buy new bars than to reform the worn bars. The important object of my invention is the production of a mobile reforming plant, that is, a complete plant on wheels so that it can be drawn alone or in a train to the point on the right of way where worn splice bars are to be replaced, so that these worn bars can be reformed and restored to usefulness directly on the job.

One important feature of my invention is the adaptation of the plant apparatus and equipment to the space afforded by ordinary freight car dimensions.

Another important feature is the inclusion in such plant, not only of forging or pressing mechanism, but also an annealing furnace, and retempering apparatus, together with conveyor mechanism for automatically carrying the bars from one field of operation to the next.

Another important feature of the invention is the disposition or alignment of the plant apparatus in one or more cars so that the worn plates can be fed in at one end of the car or train, carried to the furnace to be annealed, then subjected to reforming operation in the press apparatus, then carried through an oil bath for retempering, and then delivered at the other end of the car or train ready for reapplication to the track.

Another important feature is the provision of conveyor members which are mov-

able or detachable to be stowed inside the cars in order to permit the cars to be closed when the plant is not in operation and is being transported.

A further feature of importance is the adaptation of walls of the car for swinging or other movement to provide additional floor space and sheltering roof thereover.

The above enumerated and other features of my invention are shown incorporated in the structure disclosed on the drawings, in which drawings,

Figure 1 is a vertical sectional view of one car containing the splice bar conveyor and annealing apparatus;

Figure 2 is a similar section of a second car containing the pressure reforming mechanism and the retempering apparatus;

Figure 3 is a section on line III—III of Figure 1;

Figure 4 is a horizontal sectional view of the car of Figure 2 showing the reforming mechanism and retempering mechanism in plan elevation;

Figure 5 is an enlarged section on line V—V of Figure 1;

Figure 6 is an enlarged section on line VI—VI of Figure 2;

Figure 7 is an enlarged horizontal sectional view of the coupled ends of the cars of Figures 1 and 2, showing the annealing apparatus and reforming apparatus and the interconnecting conveyor mechanism;

Figure 8 is a vertical section of the coupled ends of the cars showing the annealing apparatus and reforming apparatus in side elevation;

Figure 9 is a side elevation of the end of a chute showing the supporting hook arrangement.

Figure 10 is an enlarged sectional view on plane X—X of Figure 3.

The plan shown comprises two cars A and B in which the various apparatuses are distributed. The cars A and B each comprise a suitable chassis 1 mounted on trucks 2 and supporting a floor 3. In the car A is located the annealing furnace designated as a whole by C. It comprises the bed 4 and the top wall or arch 5, preferably built up

of suitable heat refractory material. The furnace is supported on steel cross beams 6 resting on the floor of the car. The front wall 7 of the furnace has the inlet opening 8 above the end of the wall 4 and the wall 4 inclines downwardly toward the rear end of the furnace as clearly shown in Figure 1. The top wall 5 extends rearwardly a distance beyond the bed wall 4 and is connected 10 with the rear wall 9 by the inclined or sloping deflector wall 10.

Framework 11 extends across the furnace from the lower end of the rear wall 9 to within a short distance of the inner end of 15 the wall 4 and supports a grating or tuyère structure 12 for the flow of air into the furnace. The wall 9 has the inlet passage 13 through which combustible such as gas or oil is delivered by a suitable injecting device 20 14 mounted on the wall 9 in front of the passage 13. The injected combustible is mixed with air flowing upwardly through the tuyère structure 12 and the combustion mixture is ignited and the flames are deflected and drawn through the furnace, the 25 products of combustion escaping through a suitable stack 15 rising from the front end of the furnace. The flame and heat are directed against the bed wall 4 on which are secured guides 16, shown in the form of rail lengths, for supporting the splice bars or other objects to be annealed.

At the end of the car A in front of the 30 furnace is located a supporting frame 17 on top of which is a cross shaft 18 journaled in bearing structures 19. The shaft is adjacent to the ends of the furnace rails 16 which project outwardly a distance through the furnace inlet opening 8. At one end the shaft has a sprocket wheel 20 connected by a chain belt 21 with the sprocket pinion of a motor 22. Between the projecting ends of the rails 16, the shaft carries a pair of sprocket wheels 23 connected by chain belts 24 with a pair of sprocket wheels 25 on a shaft 26 journaled in the outer end of a frame 27 which at its inner end is connected to the shaft 18 to swing relative thereto. The adjacent end 35 50 wall of the car has an opening or doorway 28 through which the frame 27 extends, and when the apparatus is in use the frame is inclined and extends downwardly close to the ground and it is supported in such inclined position by the cross bar 29 on the frame 17. The chain belts 24 have the carrier fingers 30 which receive the splice bars to be reformed and when the belts travel the bars are carried upwardly and deposited by the carrier fingers 60 65 onto the projecting ends of the rails 16, and the bars are then shifted downwardly along the inclined rails and through the furnace to be heated and annealed preparatory for the reforming operation in the press.

65 Referring to Figures 3 and 10, a simple

means is shown for shifting the bars through the furnace. A pusher member 100 is provided supported by and shiftable on a support 101. The pusher member has the opening 102 for receiving the cam 103 secured to the shaft 18 so that as the shaft rotates the pusher is reciprocated laterally. Referring to Figure 10, the pusher member is withdrawn and a bar b has just been deposited on the rails 16 by the conveyor chain 24. As the shaft 18 continues to rotate the cam 103 will shift the pusher member into engagement with the bar b so that this bar together with the bars in advance thereof are shifted along the rails 16 to make way for the next bar carried up by the chain 24.

Provision is preferably made for stowing this carrier or conveyor structure in the interior of the car when the plant is not in use. To accomplish this, the frame 27 may be made detachable from the shaft 18 as for example by means of hooks 31 at the inner ends of the frame which can be readily hooked over the shaft 18 when the conveyor is to be used. Such arrangement is shown in Figure 9. When the frame is unhooked from the shaft the chain belts 24 will slacken and then the frame can be laid down in the car A alongside the furnace structure.

In the adjacent end of the car B, which is coupled to the car A by suitable coupler mechanism 32, is located the forming press designated as a whole D. Such press comprises a base 33 and a reciprocating head or ram 34 slidable on the posts 35. The ram may be reciprocated mechanically, hydraulically or pneumatically, or by a combination of such forces delivered by suitable mechanism driven by a motor 36. The base and ram of the press support suitable die members 37 and 38 for receiving and reforming the hot annealed splice bars. The treated bars are delivered from the furnace to the press by a chute structure shown as comprising side walls 39 and 40 connected by cross shafts 41 on which journal rollers 42. On the furnace structure and on the base of the press are secured the vertically slotted brackets 43 and 44 respectively which receive the projecting ends of the end shafts of the chute to thus support the chute for the travel along the rollers of the heated bars on their way to the press. A sheet metal apron 45 extends from the inner end of the bed wall 4 of the furnace toward the chute and forms an incline down which the bars travel after leaving the end of the furnace rails 16.

In the arrangement shown, the press is adapted to receive the splice bars end on, but when the heated bars leave the furnace they are at right angles to the chute structure. To turn the bars so that they will reach the chute parallel therewith, a turning pin 46 is provided on the apron 45 which engages with and holds one end of the bars and causes

them to swing around 90 degrees into parallelism with the chute so that they will be delivered end on to the press. The chute is slightly lower at the press end so that the bars will travel by gravity toward the press.

5 As the bars travel along the chute rollers the loose scale or other foreign matter thereon will drop therefrom. The bars can be thoroughly cleaned by means of a wire brush or other apparatus while they are traveling along the chute so that when they enter the press they will be clean for accurate reforming operation. Sections 47 and 48 of the adjacent end walls of the cars A and B may be hinged to be swung down to form a continuation of the car floors to furnish adequate footing for the workmen at the chute structure and around the press.

10

15

The workman sees that a bar is accurately positioned on the lower die member 37 and then starts the ram to bring down the upper die member and the hot annealed bars will then be reformed. During such reforming operation in the press, the bolt holes of the bars may become distorted and I therefore preferably provide a suitable machine 49 driven by a motor 50 for operating a suitable tool 51 to engage through the bolt holes and restore them to normal. Guide rails 52 may be provided for supporting the bars on their way from the press to the hole reforming machine.

After annealing and reforming of the splice bars, they must be retempered and cooled. For this purpose I provide an oil bath in a suitable tank 53 mounted in the car B in alignment with the forming machine. At the bottom of this tank at the ends thereof are shafts 54 and 55 having sprocket wheels 56 for driving a pair of parallel carrier chain belts 57 and 58. At the rear end of the tank and at the top thereof is journalled a drive shaft 59 driven by a chain belt 60 from an electric motor 61. Through chain belts 62 and suitable sprocket wheels the drive shaft 59 drives the shaft 55 and thereby the carrier belts 57 and 58. In front of the tank is journalled a shaft 63 driven from the shaft 59 by a chain belt 63' and suitable sprocket wheels on the shaft. The shaft 63 carries a pair of sprocket wheels 64 connected by chain belts 65 to drive an idler shaft 66 journalled in bearing structures 67 mounted on the floor of the car, the belts 65 having carrier fingers 68 and serving to receive the reformed bars from the reforming machine and to hoist them for delivery into the oil bath, an apron 69 receiving the bars and guiding them onto the carrier belts 57 and 58 in the bath tank. Guide rails 70 support the bars on their way from the machine 49 to the belts 65, the bars being positioned by the workman so that they will be received crosswise by the belts 65 and travel in this position with the belts 57 and 58.

As the reformed bars are carried through the oil on the belts 57 and 58, they are retempered and cooled, and at the end of the tank they are received by the carrier fingers 71 on the belts 62 and hoisted out of the tank 70 and delivered to an apron 72 from which they slide onto the chute structure 73 which extends laterally and downwardly through an opening 74 in the side of the car, and the finished bars travel lengthwise on the chute 75 and are deposited on the ground or in a suitable receptacle. The chute 73 preferably has rollers 75 so that the bars will readily travel down the chute, and the chute may be detachably supported by a bracket structure 76 on the end of the tank 53, so that when the apparatus is not in use the chute can be removed and placed within the car.

In order to keep the oil in the tank 53 cool, I circulate it through a piping coil 77 in the cooling tank 78 supported at the top of the car above the tank 53, and water or ice in the tank 78 may serve as the cooling medium. The motor 61 which drives the various belts for carrying the reformed bars to and from the tank 53 is also connected to drive a pump 79 for circulating the oil through the coil 77. The pump draws the oil through the piping 80 and delivers it to the coil 77 through a pipe 81, the cooled oil returning 85 to the tank 53 through the pipe 82.

As clearly shown in Figures 5 and 6, the side walls of the cars are divided into upper sections 83 hinged along the top of the cars, and lower sections 84 hinged along the floor 100 of the cars. When the plant is in operation, the sections 83 are elevated to form continuations of the roof of the car and when the sections 84 are lowered to horizontal position they form extensions to the floor of the 105 car. The floor space for the workmen is thus increased and they are protected overhead, and the cars will be well ventilated. As already explained, the hinged end wall sections 47 and 48 of the cars will, when swung 110 down, form flooring space between the car ends.

Briefly repeating the operation of the plant, the worn-out splice bars are fed to the carrier belts on the hoisting frame 27 115 and delivered to the projecting ends of the guide rails within the annealing furnace, and the bars travel slowly through the furnace to be thoroughly annealed and prepared for the reforming operation in the press. As the bars leave the furnace they encounter the turning pin 46 and they swing around on the apron 45 to be parallel with the chute structure 39, 40 along which they travel by gravity to the press D where they are properly 120 located relative to the die members to be reformed when the press ram is forcibly brought down. The bars are then transmitted to the machine 49 which restores their bolt holes to normal and then the bars are hoisted 125 130

by the carrier belts 65 to the apron 69 down which they slide to the carrier belts 57 and 58, and on their passage through the oil in the tank 53 the bars are retempered and 5 cooled. The hoisting belts 62 then receive the bars and hoist them up and deposit them on the apron 72 from which they fall onto the chute structure 73 to be delivered to the ground or into a suitable receptacle.

10 When the plant is to be transported, the hoisting structure 27 is unhooked from the shaft 18 and stowed away inside of the car A as has already been explained. The chute structure 39 is removed from its supporting

15 brackets 43 and 44 and also stowed inside of the car, and likewise the chute structure 73 is detached and stowed inside of the car B. The hinged sections of the car walls are then swung back into normal position to close the 20 cars. The cars then can be coupled to a locomotive or in a train so that the reforming plant can be transported to some other field of operation.

I thus produce a compact reforming plant 25 which can be readily transported to the location where a track is being repaired and worn splice bars are to be removed, so that the bars can be reformed on the job and reapplied to the rails.

30 I do not, of course, desire to be limited to the exact construction, arrangement and operation disclosed and described as changes and modifications are possible without departing from the scope and principle of the

35 invention.

I claim as my invention:

1. In a mobile reforming plant of the class described, the combination of two railway cars, a furnace in one of said cars for heating 40 the objects to be reformed, a reforming press and a cooling bath in the other car, conveyor mechanism for conveying to said furnace the objects to be heated, a detachable chute for conveying the heated objects from 45 the furnace to the press, conveyor mechanism for receiving the reformed objects from the press and for conveying them to the cooling bath and for discharging the objects from said bath, and means for receiving and 50 delivering the discharged objects.

2. In a mobile reforming plant for reforming worn-out splice bars, the combination of two railway cars, an annealing furnace in the first car, reforming press mechanism in said second car, a cooling bath in 55 said second car, conveyor mechanism in said first car extensible through an end thereof for receiving worn bars and conveying them 60 to said furnace, a detachable chute extending between the cars for conveying the heated bars to the press mechanism, conveyor mechanism for receiving the reformed bars and conveying them to and from said cooling 65 bath, and a detachable chute extending out-

wardly from said second car for delivering the cooled finished bars to the exterior.

3. In a bar reforming plant, the combination of an annealing furnace, press structure, a chute for conveying the heated bars 70 from said furnace to said press structure, means for causing the bars to travel sideways through said furnace, and means at the outlet of said furnace for automatically turning said bars to cause travel thereof 75 lengthwise on said chute and into said press structure.

4. In a bar reforming plant, a railway car, a furnace extending lengthwise of said car, a conveyor shaft journaled in said car adjacent to the inlet end of said furnace, a frame 80 detachably connected at its inner end to said shaft and adapted to extend through the end of said car toward the ground, means for driving said shaft, a second shaft journaled on the outer end of said frame, sprocket wheels on said shaft and conveyor belts thereon having conveyor fingers, said belts serving to receive objects to be heated and to convey them to the furnace, said frame by hooking 85 engagement with said shaft being adapted to be unhooked and stored inside of said car, a chute structure detachably secured to the rear end of said furnace and extensible through the adjacent end of the car to receive heated 90 objects from the furnace and deliver them to the exterior of the car, and means for guiding the heated objects from said furnace onto said chute.

5. In a bar reforming plant, the combination of a railway car, a furnace extending lengthwise in said car, a drive shaft journalled in said car adjacent to the inlet end of said furnace, a conveyor structure comprising conveyor belts driven from said shaft, and a frame having detachable connections with said shaft and adapted to be extended outwardly through the adjacent end of said car or to be detached and stowed within the car, and a chute extending from the inner end of said furnace through the adjacent end of the car for delivering heated objects to the exterior of the car, said chute being detachable whereby it may be stored within the car.

6. In a reforming plant of the class described, the combination of a railway car, a furnace extending lengthwise of said car, a driving shaft journaled adjacent to the inlet end of said furnace, conveyor mechanism comprising conveyor belts driven from said shaft and a supporting frame extensible through the adjacent end of said car to the exterior to receive objects to be heated and convey them to the furnace, said frame being detachable whereby it may be stowed within the car when not in use, a chute extending from the inner end of said furnace for delivering heated objects from the furnace to the exterior of the car, the objects being delivered by said conveyor mechanism to

travel sidewise through said furnace, an apron extending from the furnace outlet to said chute, means for turning the bars on said apron to cause them to travel lengthwise on said chute, and a support for said chute, said chute being detachable from said support whereby it may be stored within the car when not in use.

7. In a bar reforming plant, the combination of an annealing furnace, means for feeding bars to be heated to said furnace and for causing them to travel sidewise through the furnace, a delivery chute extending from the outlet of the furnace, an apron for guiding the bars to said chute, and an abutment on said apron in the path of one end of the bars as they issue from said furnace for causing said bars to turn on said apron into position to travel lengthwise along said chute.

20 8. In a bar reforming plant, the combination of a railway car, press structure at one end of said car, means for feeding heated bars through the adjacent end of said car and to said press structure to be reformed therein, a cooling bath extending lengthwise of said car in alinement with said press structure, conveyor mechanism for receiving the reformed bars from said press structure and conveying them through and from said bath, 30 and a delivery chute extending from the end of said bath downwardly and laterally through the side of said car to deliver the finished bars.

9. In a bar reforming plant, the combination of a railway car, press structure at one end of said car, means for feeding heated bars through the adjacent end of said car and to said press structure to be reformed therein, a cooling bath extending lengthwise of said car in alinement with said press structure, conveyor mechanism for receiving the reformed bars from said press structure and conveying them through and from said bath, and a delivery chute extending from the end of said bath downwardly and laterally through the side of said car to deliver the finished bars, said chute being detachable whereby it may be stored within the car when not in use.

50 10. In a bar reforming plant, the combination of a railway car, press structure at one end of said car and a cooling bath extending lengthwise along the other part of the car, means for feeding heated bars into the end of said car to said press structure to be reformed therein, conveyor mechanism comprising conveyor belts and supporting shaft therefor, said conveyor mechanism receiving the reformed bars and conveying them 55 through and from said bath, a discharge chute extending from the discharge end of said bath for receiving the finished bars and delivering them to the exterior of the car, a cooling coil for the bath fluid, a pump for 60 circulating the fluid through said cooling

coil, and a motor for driving said conveyor mechanism and said pump.

11. A mobile bar reforming plant comprising two railway cars coupled together, an annealing furnace extending lengthwise in the first car, hoisting conveyor mechanism extensible from the first car toward the ground for conveying worn bars to the furnace, press structure in said second car at the coupled end thereof and a cooling bath extending lengthwise in the other part of said car, a transfer chute extending from the furnace outlet in the first car and to the press structure in the second car for transferring the heated bars from the furnace to the press structure for the reforming operation, conveyor mechanism comprising conveyor belts for receiving the reformed bars and conveying them through and from said bath, a delivery chute for receiving the bars discharged from said bath and conveying them to the exterior of the car, a cooling coil for the bath fluid, a pump for circulating the fluid through said coil, and a motor for driving said pump and said bath conveyor mechanism.

12. In a mobile reforming plant, the combination of two railway cars coupled together, an annealing furnace extending lengthwise in the first car, press structure and a cooling bath located in the other car, hoisting conveyor mechanism extensible from the end of the first car for conveying worn bars to the furnace, a chute extending between the cars for conveying the heated bars to the press structure, conveyor mechanism for receiving the reformed bars and conveying them through and from the cooling bath, a chute structure for receiving the cooled bars and delivering them to the exterior of said second car, hinged wall sections for the adjacent ends of the cars adapted to be swung downwardly to form floor space between the cars in continuation of the floors of the cars, and the side walls of said cars being divided into lower sections and upper sections, said lower sections being hinged along the floor line of the cars to be swung downwardly to form extended floor space, and the upper sections being hinged along the tops of the cars to be swung upwardly to form overhead protection for the extended floor space.

13. A mobile reforming plant for the purpose described comprising a conveyance, an annealing furnace and a reforming press and a cooling bath in said conveyance, means for automatically conveying bars to be reformed to said furnace, means for conveying the bars through the furnace, means for automatically conveying the bars from the furnace to said press, means for automatically conveying the bars from said press to and through said bath, and means for automatically receiving the bars from said bath and conveying them to the exterior of said conveyance.

14. A mobile reforming plant for reforming worn out railway splice bars, comprising a conveyance, a furnace device, a press device, a punch device, and a cooling bath device, said devices being all mounted in a row in said conveyance, and means for successively conveying splice bars through said devices.

In testimony whereof I have hereunto subscribed my name at Chicago, Cook County, Illinois.

LAWRENCE S. WILBUR.
